DESIGN FOR A LIPSTICK CASE OR SIMILAR ARTICLE

William H. Leavin, New York, N. Y.

Application November 7, 1947, Serial No. 142,384

Term of patent 7 years

(Cl. D86—10)

To all whom it may concern:

Be it known that I, William H. Leavin, a citizen of the United States of America, residing in New York, county of New York, and State of New York, have invented a new, original, and ornamental Design for a Lipstick Case or Similar Article, of which the following is a specification, reference being had to the accompanying drawing, forming part thereof.

Fig. 1 is a front perspective view of a lipstick case or similar article, showing my new design.

Fig. 2 is a top plan view.

The back of the lipstick case is substantially like the front shown in Figure 1.

I claim:

The ornamental design for a lipstick case or similar article, substantially as shown and described.

WILLIAM H. LEAVIN.
